UNITED STATES PATENT OFFICE

ADOLPHE HENRI RENÉ JOSEPH BOISSIERE, OF BRUSSELS, BELGIUM

PISTON ENGINE

Application filed March 14, 1929, Serial No. 346,967, and in Belgium March 15, 1928.

The present invention relates to engines with pistons travelling in opposite directions, in which the elements having a reciprocating movement in the same cylinder are located 5 on the same axis and are exactly balanced.

The motor according to the present invention is characterized in that one of the spaces of variable volume, in which the work of the driving fluid, in the case for instance of an 10 internal combustion engine, is carried out and the bottoms of which are constituted by pistons moving in opposite directions, has its lateral walls formed by a cylindrical sleeve, which forms part of one of the pistons and 15 in which the other piston is adapted to move, whilst both pistons are caused to cooperate to the compression of the driving fluid. The engines built according to this principle differ, of course, according to the nature of the fluid 20 employed and according to their cycle of working.

The invention will be described hereafter, merely by way of example, as applied to an internal combustion engine, in which the two 25 pistons moving in opposite directions, one of which forms a cylindrical sleeve for the other, act, on the other hand, by means of their other faces, on the combustible mixture, which they suck and compress in the chambers or spaces formed between each of the 30 pistons and the corresponding end of the outer casing of the engine or a stationary piston or plug. A motor constructed in this way is diagrammatically illustrated on Fig. 1 of the accompanying drawing, which is a longitudinal sectional view thereof, whilst Figs. 2 35 and 3 are diagrammatic views illustrating the position of the pistons and the various ports at both ends of the stroke of said pistons.

With reference to these figures, the engine 40 comprises a casing 1 in suitable material, in which are formed cooling chambers and the various fluid distributing and connecting channels which may be required. The inner 45 surface of the casing 1 is formed as a cylinder 2, in which shifts a piston 5, a second piston 6 shifting inside said first piston 5. The cylinder 2 is closed at one end by a head 3, whilst its other end is connected with the 50 crank case 4 on which the casing 1 is mounted.

Both pistons 5 and 6 are formed of the properly so called piston and of a cylindrical sleeve, the inner and outer surfaces of which are turned. The piston 5 moves in the cylinder 2 and the inner cylindrical surface of its 55 sleeve 7 acts as cylinder for the piston 6, the sleeve 8 of which is outwardly guided by the sleeve 7 and inwardly guided by an element 9, which can be compared to a stationary piston and which is rigidly secured to the casing 60 1 or the crank case 4. Piston rings or other means to secure the fluid-tightness of the pistons are provided between the various pistons and their respective cylinders.

In an engine constructed according to the 65 invention, there are three spaces of variable volume: firstly, the space enclosed by the portion of the cylinder 2 comprised between the head 3 and the piston 5; secondly, the space in which works the driving fluid and which 70 is contained inside the sleeve 7 and between the pistons 5 and 6; and thirdly, the space comprised between the sleeve 8, the piston 6 and the stationary piston 9. As will be described hereafter, the necessary ports are 75 formed, in the appropriate spots, in the casing 1 and in the sleeves 7 and 8, and channels are provided to connect to one another the various above-mentioned spaces.

The driving shaft 10 is formed with a crank 80 shaft having three cranks per cylinder. The cranks corresponding to each piston of a cylinder are at 180° to one another. The central crank 11 is driven from the lower piston 6, through the medium of a central connecting 85 rod 12, whilst each of the lateral cranks 13 receives half of the efforts transmitted from the piston 5 through the medium of connecting rods 14. For this purpose, the connecting rods 14 are pivotally mounted on pins 15 projecting outwardly of the sleeve 7. This arrangement of the cranks and connecting rods allows the opposite movements of the pistons 5 and 6 to be effected with a perfect centering 90 of all the efforts. Moreover, the weights of each piston with its sleeve and of the connecting rods being exactly equal, permits of 95 accurately balancing all the elements which are given a reciprocating movement, so that not the slightest vibration, nor any other re- 100

action than that of the driving couple can be imparted to the framework. The engine is, of course, fitted with suitable devices for the lubrication and for other accessory functions.

5 In the case of an internal combustion engine employing a volatile combustible mixture, such as a mixture of gasoline and air, which has to be sucked, compressed, ignited by means of an electric spark, expanded and discharged, the arrangement of the fluid distribution means and its working are as follows: the induction pipe 16 coming from the carburettor is divided into two pipes leading to the ends of the induction and compression chambers 2 and 17. The ports 18 and 18' of these pipes are only uncovered when the pistons reach the end of their respective strokes, i. e. when the pistons 5 and 6 are in the position in which they are nearest to each other 10 in the central portion of the casing. The ports 18 are then uncovered by the upper edge of the piston 5 and the ports 18' register with corresponding ports 19, pierced through the sleeve 8 of the piston 6, and with port 30 15 pierced in the sleeve 7, which ports coincide at that moment (see Fig. 3). The combustible mixture then flows into the spaces 2 and 17, due to the depression which has been produced therein by the pistons coming 20 nearer. As soon as the movement of the pistons in the opposite direction has commenced, the ports 18, 18' are again covered, so that the combustible mixture filling the chambers 2 and 17 is compressed into the 25 channel 26 up to the desired extent, which in practice is generally small.

When this extent of compression is reached and thus when the pistons have come to the outer ends of their stroke, under the action 30 of the expansion of the previous charge, ports 20, formed in the sleeve 7 of the piston 5, uncover the channels 21 leading to the exhaust pipe 22 (Fig. 2). At the same time, the ports 23, formed in the sleeve 7, and the 35 ports 24 in the sleeve 8, which coincide at this moment with the ports 25 of sleeve 7, uncover the inlets to the connecting channels 26, which terminate at the ports 23 and allow the slightly compressed fluid to flow into 40 the upper portion of the work cylinder. The result of this is that not only are the combustion products discharged under the action of their own pressure, but they are, moreover, scavenged or swept away by the fresh 45 gases flowing into the cylinder at its other end with an eddying movement due to the 50 inclination of the inlet ports.

When approaching one another, the pistons 5 and 6 finish the compression of the 55 combustible mixture, while the inlet ports have again been covered from the start of the approaching movement of the pistons.

When the pistons have come back to the 60 central end of their strokes, the electric spark 65 is produced at the spark plug 27 and the mix-

ture is ignited. The mixture then burns and expands during the next stroke of the pistons moving apart from one another and the cycle starts over again.

It will be understood that in this way the 70 motor according to the invention works as a two-stroke motor, the theoretical advantages of which are well known. The cooling of the casing 1 is effected by means of a cooling fluid passing through chambers 28 75 formed in said casing.

The ports 20 and 30 pierced in the sleeve 7 may be very close to each other and may even be formed as one port, as shown on Fig. 1, where numerals 20 and 30 indicate 80 one and the same port.

It must be understood that the invention is not restricted to its application to internal combustion engines, but that it can be applied to piston engines of all kinds and making 85 use of any driving means whatever, when the necessary arrangements, corresponding to those engines, are brought to it. The device with its accessory parts, according to the invention, can thus be applied without the slightest difficulty to engines making use of mineral oils of high specific gravity and also to steam engines, when a few modifications are brought to it. 90

On the other hand, the device according to 95 the invention can also be used as a compressor and even compound compression can be effected with it when the spaces 2, 17 and 29 are properly made use of and when the thickness of all the sleeves is varied in a 100 suitable way, without changing the equality of the weights of the pistons, by using appropriate metals therefor, and when said spaces are connected by suitably arranged means.

In all cases, the principal advantages of 105 the invention are obtained, i. e. a high thermal efficiency and an exact mechanical balancing, this result being due to the various constructional principles of the invention, that is the construction of motors or compressors with pistons moving in opposite directions, in which each piston is provided with a sleeve, one of said sleeves acting as cylinder for the other piston, the second sleeve acting as cylinder for a stationary piston or plug, whilst the outer casing, which is closed by a cylinder head, acts as cylinder for the first piston. 110

It must also be observed that the ignition 115 must not necessarily take place in the work chamber, but that the spark plug can also be advantageously arranged in the connection channel 26; the result of this is, that, at the moment when the inlet ports are uncovered, a violent flame penetrates into the work 120 chamber and almost instantaneously ignites the whole charge, whilst the walls of the sleeves cannot be heated to a harmful extent, due to the fact that they move and come in contact with cooled surfaces. 125

I claim:

walls of said casing, both said sleeves and said intermediate element being adapted to register at a given moment of the stroke of the pistons, the arrangement being such that the working fluid is let in into the spaces of variable volume comprised between the closed end of the casing and the first piston and between the second piston and said intermediate element when the pistons are in their nearest position in relation to each other, that said fluid flows from both said spaces into the third space of variable volume comprised between the two pistons during the separating movement of the pistons, and that the fluid flowing in said last-mentioned space sweeps away the fluid of the previous charge when the pistons are in their farthest relative position.

6. In a piston engine, comprising in combination: a hollow casing, a crank case connected to one end of said casing, means to close the other end thereof, a piston with a sleeve depending therefrom adapted to move in said casing acting as cylinder therefor, a second piston with a sleeve depending therefrom adapted to move in said first sleeve acting as cylinder therefor, a stationary element fitting in said second sleeve and acting as stationary piston therein, means connecting both said sleeves to the driving shaft rotating in the crank case, the arrangement being such that the two pistons move in opposite directions, and the weights of the pistons, sleeves and means connecting same to the driving shaft being such that all the reciprocating elements are perfectly balanced, fluid supply and discharge channels, ports formed in the walls of said casing, both said sleeves and said intermediate element being adapted to register at a given moment of the stroke of the pistons, the arrangement being such that the working fluid is let in into the spaces of variable volume comprised between the closed end of the casing and the first piston and between the second piston and said stationary element, when the pistons are in their nearest position in relation to each other, that said fluid flows from both said spaces into the third space of variable volume comprised between the two pistons during the separating movement of the pistons, and that the fluid flowing in said last-mentioned space sweeps away the fluid of the previous charge when the pistons are in their farthest relative position, the ports allowing the fluid to pass into said last-mentioned space being inclined so that an eddy movement is imparted to said inflowing fluid.

7. In an internal combustion engine, comprising: a cylindrical hollow casing, cooling chambers in the walls of said casing, a head closing one end of said casing, a crank case connected to the other end thereof, a piston with a cylindrical sleeve depending

therefrom adapted to move in said cylindrical casing, a second piston with a cylindrical sleeve depending therefrom adapted to move in said first cylindrical sleeve, a stationary cylindrical element secured to a stationary part of the engine and fitting in said second cylindrical sleeve, said stationary element being hollow and open at its end adjoining said second piston, means provided between said first piston and said cylindrical casing, between said second piston and said first cylindrical sleeve and between said stationary element and said second cylindrical sleeve to ensure the fluid-tightness thereof, means connecting both said sleeves to the driving shaft rotating in the crank case, the arrangement being such that the two pistons move in opposite directions, and the weights of the pistons, sleeves and means connecting same to the driving shaft being such that all the reciprocating elements are perfectly balanced, connecting channels adapted to set the three spaces of variable volume comprised between the pistons, the head and the stationary element in communication with one another, ports formed in the walls of said casing, both said sleeves and said stationary element being adapted to register at a given moment of the stroke of the pistons, the arrangement being such that, when the pistons are in their nearest relative position, the working fluid flows into the spaces of variable volume comprised between the closed end of the casing and the first piston and between the second piston and said stationary element, that when the pistons move apart, the fluid from said two spaces flows into said connecting channels, that at the end of the separating movement of the pistons said compressed fluid flows from said connecting channels into the space of variable volume between the two pistons and sweeps away the fluid of the previous charge thereout, that when the pistons move nearer to each other, the fluid in the last-mentioned space is compressed and the fluid in the first two spaces is expanded, and a spark plug adapted to ignite the charge in said space comprised between the two pistons at the end of the compression movement of the pistons, whereby the engine works as a two stroke engine.

In testimony whereof I signed hereunto my name.

ADOLPHE HENRI RENÉ JOSEPH BOISSIERE.
